FILLING CLAMPING AND PARTING MEANS FOR LOOMS.

1,427,638.

Specification of Letters Patent. Patented Aug. 29, 1922.

Application filed August 23, 1921. Serial No. 494,526.

To all whom it may concern:

Be it known that I, ALONZO E. RHOADES, a citizen of the United States, resident of Hopedale, county of Worcester, State of Massachusetts, have invented an Improvement in Filling Clamping and Parting Means for Looms, of which the following description, in connection with the accompanying drawing, is a specification, like characters on the drawing representing like parts.

This invention relates to automatic filling replenishing looms in which a mechanism is provided to clamp and part adjacent the end of the shuttle the filling extending from the selvage of the cloth being woven to the filling carrier about to be abandoned.

The object of the invention is to provide a simple and efficient means for effecting the closing movement of this filling clamping and parting mechanism.

The object of the invention is further to provide such a closing means operable only upon the actuation of the transferring means by which a fresh filling carrier is transferred 25 from the magazine or supply to the lay so that there will be no danger of the running filling being severed until and unless an actual operation of the transferring means takes place.

30 The object of the invention is further to provide such a closing means as will render unnecessary extreme accuracy in the assembly and adjustment of the filling clamping and parting mechanism and as will give or 35 yield upon the occurrence of any abnormal resistance to the operation of the parts.

These and other objects and features of the invention will appear more fully from the accompanying description and drawings 40 and will be particularly pointed out in the claims.

In the drawings:

Fig. 1 is a view in vertical cross section looking toward the inside of the transfer end 45 of the loom with only such portions of the mechanism shown as is necessary to a disclosure of the present invention.

Fig. 2 is a detail in plan and partially in horizontal cross section showing the parts 50 attached to the loom in the preferred form of the invention.

The automatic filling replenishing loom illustrated is of the well known Northrop type and as the construction and operation

of this type of loom is familiar to those skilled in the art, it is unnecessary to illustrate or describe anything more than those parts particularly concerned with the present invention. So, also, the filling clamping and parting means illustrated is of a well known and familiar type and for the same reason needs no detailed illustration or description.

In this type of loom the frame, one side of which 1 is illustrated, supports at the front the usual breast beam 2 and upon this frame swings the lay 3. The shuttle 4 is picked back and forth across the lay and is shown boxed at the transfer side of the loom. Upon this side of the loom is mounted the hopper or magazine 5 which carries the supply of fresh filling carriers one of which is illustrated as a bobbin 6 ready for transfer into the shuttle boxed therebeneath. Transfer is effected in this type of loom by a transerrer 65 arm 7 having a hub 8 journaled on a stud 9 mounted in the stand of the magazine 5 by which it is secured to the breast beam 2.

When the running filling in the shuttle weaving the cloth has become substantially exhausted, suitable and familiar mechanism forming no part of the present invention indicates the substantial exhaustion of the filling and through suitable connections rocks a rod or shaft 11 extending along the front of the loom frame. This shaft has projecting rearwardly therefrom an arm 12 engaging at its rearward end a stud 13 on a swinging shuttle feeler 14 pivoted on the frame at 15. This shuttle feeler is arranged to swing 85 across the path of the shuttle if it is properly boxed ready for transfer, but if the shuttle is not properly boxed, then the shuttle feeler strikes the shuttle and the completion of its swinging movement is prevented. 90 The shuttle feeler has a slotted projection 16 co-operating with the stud 17 on a dog 18 pivoted to an arm 19 depending from the transerrer arm hub 8.

It will therefore be seen that upon the call 100 for filling replenishment, the starter rod 11 being rocked, the arm 12 is raised, the shuttle feeler 14 is swung rearwardly and if the shuttle is properly boxed the dog 18 is elevated into the path of a bunter 20 on the 105 lay. Consequently, as the lay beats up, the transerrer arm 7 is swung downwardly transferring the fresh filling carrier into the

shuttle on the lay and ejecting from the shuttle the substantially exhausted filling carrier. If, however, the shuttle is not properly boxed, the shuttle feeler strikes against 5 it and consequently the movement of the parts is not sufficient to bring the dog 18 opposite the bunter 20 and therefore no transfer takes place. All of this mechanism, construction and operation, is familiar to those 10 skilled in the art.

The filling extending from the selvage to the filling carrier to be abandoned must be severed and it is customary to sever it adjacent the end of the shuttle and again close 15 to the selvage. For the former purpose a filling clamping and parting mechanism is provided and is commonly mounted on the shuttle feeler which affords a convenient support. In the form illustrated this filling 20 clamping and parting mechanism consists simply of a pair of fixed blades 21 secured to the upper end of the shuttle feeler and a movable blade 22 mounted between the fixed blades on a pivot 23. The movable blade 22 is shown as swinging upwardly at its effective end to clamp and part the filling and consequently it may be swung to operative position by a downward pressure on its forward end 24. A pin 25 mounted in the shuttle 25 feeler and projecting through a hole 26 in the movable blade limits the extent of the closing movement of the blade. The movable blade is also provided at its forward end with a transversely extending pin 27 30 which in co-operation with the switch cam 28 pivoted at 29 on the bracket arm 30 effects the opening movement of the blade in a generally familiar manner.

In the normal position the parts stand in 40 position indicated in full lines in Fig. 1, the blades 21 and 22 holding the severed filling end of the filling carrier last abandoned. Upon the call for filling replenishment, the shuttle feeler swings rearwardly, as already 45 described, and the pin 27 riding up the forward side of the switch cam 28 swings the movable blade 22 to open position and the filling end held thereby drops out. The parts then swing forwardly to the position 50 indicated in dotted lines if the shuttle is properly boxed and the filling extending to the filling carrier about to be abandoned enters between the blades. The movable blade must now be closed in order to clamp 55 and part the filling end close to the shuttle and so that this filling end extending to the selvage may be carried forward out of the way and brought into the path of the usual temple thread cutter whereby it is severed 60 close to the selvage. This closing movement in the present invention is effected by means connected with the transerrer arm so that there can be no severance of the filling unless the transferring mechanism is actuated.

65 It will also be noted that the movable

blade must not move in its closing movement beyond a certain point or there will be danger of breaking or shearing off the pin 25. It is not an easy matter to assemble all the parts of the shuttle feeler, filling clamping and parting mechanism and to adjust these parts with respect to the lay so that accuracy of the closing movement of the filling clamping and parting means under all conditions can be maintained. One feature 75 of the invention consists in providing a yielding or give-way feature in the means for closing the filling clamping and parting means so that under all conditions the proper closing movement may be effected and then 80 further movement taken up by the yielding or give-way feature. Thus, not only is it unnecessary to adjust the parts with absolute accuracy but also if, for any reason, any abnormal resistance occurs to the movement 85 of the parts, this yielding or give-way feature prevents damage or breakage.

The closing means provided for this purpose in the preferred form illustrated comprises a bracket 31 bolted at 32 to the hub 8 90 of the transerrer arm and extending around the magazine stand 10. At its inner end this bracket is provided with a laterally projecting stud 33 on which is journaled an actuator in the form of a hub 34 having a 95 rigid arm 35 projecting rearwardly and provided with a rounded end 36 standing directly over the forward end 24 of the movable blade when the filling clamping and parting means is in its rearward or operative position. A helical spring 37 surrounds the stud 33 in a recess in the hub 34 and is connected at one end to the bracket 31 and at the other end to the hub 34 and acts normally to hold a lug 38 projecting rearwardly from the hub 100 34 against a lug 39 projecting from the bracket 31. This spring is of sufficient strength to cause the arm 35 to move with the transerrer arm and effect the closing movement of the filling clamping and parting means but is so tensioned as to allow the arm 35 to yield and the lugs 38 and 39 to separate if there is any abnormal resistance to the operation of the filling clamping and parting means or other parts or if the movable blade comes in contact with the pin 25 before the movement of the transerrer arm 110 has been completed.

It will therefore be seen that when the filling clamping and parting means has 120 moved to its rearward or operative position as the lay completes its beat-up and the bunter 20 strikes the dog 18, the transerrer arm 7 is swung downwardly carrying with it the bracket 31 and the arm 35 125 so that the end 36 of the arm strikes the end 24 of the movable blade and swings it to closing position, the arm 35 thereafter yielding if necessary. Thus, the closing movement of the filling clamping and 130

parting means is accurately and surely effected and only when the transferring mechanism is actually operated.

After transfer has been effected, the shuttle feeler swings forwardly in the usual manner and the pin 27 sliding down the front face of the cam 28 raises that cam about its pivot 29 and passes beneath the cam which then drops behind it to the position shown in full lines. Thus, the clamped and parted filling end is carried back and held in position to be severed close to the selvage by the usual temple thread cutter.

Having thus described my invention, what I claim as new and desire to secure by Letters Patent, is:

1. An automatic filling replenishing loom comprising a magazine to contain a supply of fresh filling carriers, a pivotally mounted transerrer arm acting when actuated to swing downwardly and transfer a fresh filling carrier from the magazine to the lay, a shuttle feeler movable toward and from the lay and acting when moved to its rearward position to effect the actuation of the

transferrer arm, filling clamping and parting means including a movable blade mounted on the shuttle feeler, a bracket secured to and movable with the transerrer arm, a rigid actuator arm projecting rearwardly over the movable blade when in its rearward operative position and pivotally mounted on the bracket and means permitting the actuator arm to yield upwardly and turn on its pivotal mounting upon the occurrence of any abnormal resistance, the said actuator arm, upon the actuation of the transerrer arm, striking the movable blade and moving it to closed position.

2. An automatic filling replenishing loom comprising the construction defined in claim 1 in which the bracket and the actuator are provided with co-operating stop lugs and in which a spring connects the bracket and the actuator and acts to hold the said lugs in engagement but permits the upward yielding of the actuator with respect to the bracket.

In testimony whereof, I have signed my name to this specification.

ALONZO E. RHOADES.
